UNITED STATES PATENT OFFICE

RAYMOND CARTER, OF NEW YORK, N. Y., ASSIGNOR TO EDWARD J. McNAMARA, OF GREAT NECK, NEW YORK

DESIGN FOR SCHOOL PENDANT OR SIMILAR ARTICLE

Application filed June 15, 1932. Serial No. 44,089. Term of patent 14 years.

To all whom it may concern:

Be it known that I, RAYMOND CARTER, a citizen of the United States, and a resident of the city, county, and State of New York, have invented a new, original, and ornamental Design for a School Pendant or Similar Article, of which the following is a specification, reference being had to the accompanying drawing, forming a part thereof.

In the drawing, Fig. 1 is a front view of a school pendant or similar article showing my new design; and Fig. 2 is an edge view thereof.

I claim:

The ornamental design for a school pendant or similar article as shown.

RAYMOND CARTER.
